BARREL-HEADING MACHINE.

1,153,160.

Specification of Letters Patent.

Patented Sept. 7, 1915.

Original application filed November 25, 1910, Serial No. 594,072. Divided and this application filed June 3, 1911. Serial No. 631,067.

To all whom it may concern:

Be it known that I, HENRY C. HERR, a citizen of the United States of America, residing at Pittsburgh, in the county of Allegheny and State of Pennsylvania, have invented certain new and useful Improvements in Barrel-Heading Machines, of which the following is a specification, reference being had therein to the accompanying drawings.

The invention relates to package heading machines and consists in the construction as hereinafter set forth.

In the drawings, Figure 1 is an elevation of the machine partly in section; Fig. 2 is an elevation viewed at right angles to Fig. 1; Fig. 3 is a vertical central section through the nailing mechanism; Fig. 4 is a sectional plan view thereof; Fig. 5 is a plan of the nail releasing mechanism; Fig. 6 is a cross section through a portion of the assorting mechanism; and Fig. 7 is a horizontal section showing the operation of the flange rolling mechanism.

The improved machine is capable of being used for the heading of packages of various constructions but as illustrated and specifically described, it is particularly designed for use in the heading of packages having cylindrical bodies formed of spiral wrappings of paper or similar material. The heads are formed of wood and are provided with the usual croze of barrel construction, but as the body is not provided with a groove the head is engaged with a chine-hoop formed of metal. This hoop has a V-shaped groove to fit the croze of the head and is of a size corresponding to the internal diameter of the body so as to be capable of entering the end thereof. The hoop is also preferably provided with a return bent flange which passes around the end of the cylindrical body and over the outer edge thereof, forming a metallic reinforcement.

The operations performed by the machine are first, the pressing of the head and chine-hoop into engagement with the end of the cylindrical body; second, the rolling down of the outer flange of the chine-hoop which is originally of the flaring form to permit the entrance of the end of the paper body; third, the automatic nailing of the head, the

nails being distributed around the body and arranged to pass through the same, the chine-hoop, and into the head in a radial direction. These operations are performed by a mechanism, the detail construction of which is as follows: The frame of the machine is preferably formed of a bed A, standards B rising therefrom, and an annular top frame C mounted at the upper ends of said standards. Centrally within this frame is a vertical movable plunger or work supporting table D which is reciprocated by suitable mechanism such as a crank E and abutment F. The plunger is guided in slide-ways G on the standard, and the crank is mounted on a shaft H driven at slow speed through the medium of the step-down gear train I from a drive shaft J, while the clutch K and trip pedal L control the cycle of movement. The arrangement is such that during each cycle the plunger or work table D is raised from and lowered again by one complete revolution of the crank. The body of the package to be headed is placed upon the work table D, the lower end engaging the circular guide D' which properly centers the work. The upper end of the body upon which the head and chine-hoop are placed, is in registration with an annular guide M and an annular abutment N, these parts operating during the rise of the plunger to force the head and chine-hoop into full engagement with the cylindrical body. To provide for slight inequality in size, the plunger D is provided with a yielding top plate D² resiliently supported on springs D³. This yielding connection is also employed for another important function, that is to provide a suitable interval of delay between the completion of engagement of the head with the body and the lowering of the work in which the flange closing and nailing operations may be performed. Thus while the movement of the crank and plunger is continuous the movement imparted to the work is intermittent.

Flange closing mechanism.—As has been already described, the chine-hoop O is provided with a return bent flange O' for fitting over the end of the paper body and this flange is originally of a flaring form to receive the end of the body and to guide it

into full engagement with the hoop. The flared flange is then closed down into close-engagement with the body by the operation of presser rolls. The rolls P are distributed about the package body and are carried by a revolute annular member which also constitutes an element in the nailing mechanism, to be hereinafter described. The member P' is supported upon the annular member C and is provided with peripheral gear teeth P² which are in mesh with the pinion P³ on the vertical shaft P⁴ intermittently driven by a bevel pinion P⁵ engaging an interrupted bevel gear wheel P⁶ on one of the members of the gear train J. This mechanism will impart an intermittent rotary movement to the annular member P' and the timing is such that the member P' begins its rotation upon the completion of the full engagement of the head with the body and continues to rotate during the interval of delay caused by the compression and expansion of the spring D³. The member P' then remains stationary during the remainder of the cycle and while the work on the plunger is being lowered.

During the intermittent rotation of the member P' the rolls P travel about the flange of the chine-hoop and the distance traveled is sufficient to cause the rolling down of all portions of the flange. As preferably constructed and as shown, the annular member P' travels during each movement one third of a revolution and as there are six rolls 35 equally spaced the operations performed thereby are equivalent to two complete revolutions of a single roll. In their normal positions the rolls P are sufficiently withdrawn from the chine-hoop to provide an unobstructed path for the latter as it is forced upward against the abutment N. During the initial movement of the member P', the rolls are brought into contact with the periphery of the chine-hoop and are held 40 there during the continued movement, this being accomplished by the following construction: Q are rockable members pivotally attached at Q' to the member P' and extending inward therefrom. The rolls P are journaled at the front ends of the members Q and the latter are normally arranged at a slight angle to the radius of the member P' being yieldably held in this position by springs Q² which draw them against adjustable stops Q³. In this position the rolls are 45 withdrawn from contact with the chine-hoop as has been already stated, but adjacent to the rolls are arranged yieldable stops Q⁴ which project from the stationary member N' on which the abutment N is formed. The stops Q⁴ project outward from the member N' into the path of movement of the rolls P during the rotary movement of the member P' and form a sufficient obstacle to temporarily arrest said roll and cause the arm Q to

swing upon its pivot. This movement will continue until the arm Q bears against an adjustable stop Q⁵ on the opposite side thereof, after which the arm Q and roll P are compelled to rotate with the member P' 70 riding from the stop Q⁴ by pressing the latter inward against the tension of a spring Q⁶. The swinging movement of the arm Q will carry the roll P inward into contact with the chine-hoop which is pressed against 75 the cylindrical body of the package and during the continued operation is rolled in firm contact therewith. At the completion of the movement the springs Q⁴ will draw the arms Q again against the stop Q⁵ withdrawing the rolls P from contact with the hopper.

Nailing mechanism.—The mechanism employed for nailing the heads to the bodies comprises first, mechanism for extracting the nails from an irregular mass in the hopper and arranging them in parallelism, second; means for periodically distributing the required number of nails into the position for handling, and third; means for driving and pressing the nails radially inward. The first of these groups of mechanism or the nail assorting means, includes a hopper R the bottom plate of which is inclined and formed with a series of V-shaped grooves R' therein. The bottoms of the grooves are of sufficient width to receive the body of the nail, but too narrow to permit the head of the nail to enter therein.

R³ is a slide having V-shaped sheet metal flanges fitting over the V-shaped ribs on the 100 bed between the grooves R'.

R⁴ is the front plate of the hopper provided with depending V-shaped lugs R⁵ with the apex of each V cut away and concaved sufficiently to permit the head of the nail to 105 pass therebeneath. These lugs fill the grooves R' with the exception of the lower portion thereof, providing only sufficient clearance for the movement of the V-shaped fingers R³.

R⁶ is a grooved guide having the slots or grooves alined with the grooves R', said guide extending in an inclined position from the hopper R.

R⁷ is a cross-head to which all of the fingers R³ are attached.

R⁸ are pitman rods connecting said cross-head R⁷ to cranks R⁹. Thus every time the cranks R⁹ are rotated the fingers R³ are given their reciprocatory movement, being 120 pressed into and withdrawn from the hopper R. In this movement the nails lying in irregular arrangement within the hopper are agitated in such a manner that they will tend to arrange themselves parallel to the 125 direction of movement of the fingers with one of the nails at the bottom of each groove R'. In this position the nail is free to move endwise beneath the lugs R⁵ out from the hopper. Here the head of the nail will en- 130

gage a stop plate R^{10} and at the same time the body of the nail will pass into registration with the slot in the guide R^6 permitting it to drop while the head remains in engagement with the guide and suspends the nail. The result is that the nails are arranged in parallelism being all suspended by their heads and being free to travel down the inclined guide to the lower end thereof. At this point there is arranged a laterally movable bar S provided with recesses S' which register with the slots in the guide and are adapted to receive the nail from each and to carry said nail laterally.

15 S^2 are pockets in the guide R^6 into which the nails are forced out of engagement with the recess in the bar S upon the lateral movement of said bar by the action of cams S^3 . The cams are formed by grooves in the under face of a bar S^4 arranged above the guide and the arrangement is such that the nails which have thus far been suspended by their heads in the guide R^6 and in the bar S , are forced into the recess S^2 which is of sufficient size to permit the passage of the head, thereby allowing the nail to fall.

With the mechanism just described, the nails are extracted from an irregular mass, are arranged in parallelism, and upon each 30 operation of the laterally shiftable bar S a predetermined number of nails are disengaged from the guide and are dropped. From this point the nails when liberated can be distributed to the proper positions for 35 nailing, but as it is necessary to arrange them radially with their heads extending outward reversing mechanism is provided by which the nails are dropped head downward. This reversing mechanism comprises 40 a rotary member T having pockets T' preferably on opposite sides thereof and which are periodically registered with the recess R^2 from which the nails are dropped. Thus upon each reciprocation of the bar S the 45 nails dropped thereby are deposited in the pockets T' , and upon the rotation of the member T , are carried into a reverse position, being held from disengagement by a segmental guide T^2 .

50 T^3 is a gate arranged beneath the member T upon which the heads of the nails when reversed temporarily rest.

T^4 are conduits beneath the gate T^2 in registration with the nail pockets T' , the arrangement being such that the gate T^3 will be withdrawn to simultaneously discharge all of the nails in their respective pockets into the conduits, through which they pass by gravity in radial directions to 55 the nailing position. For driving the parts of the mechanisms above described, beveled gear wheels U transmit rotary motion from the shaft P^4 to a horizontal shaft U' , gears U^2 on this shaft communicating movement 60 to the cranks R^9 . Motion is also transmitted

from the shaft U' through the medium of intermeshing gears U^8 to the rotary member T and the cam U^4 on the gear wheel U^8 engaging a roll U^5 on the end of the bar S , serves to reciprocate said bar which is returned by a spring U^6 . The gate T^3 is actuated by a cam V on the shaft U which positively moves it forward into a position for intercepting the nails, while springs V' effect a quick release upon disengagement with the cam. As shown the cam V has a peripheral notch V^2 therein with which a lug V^3 on the gate is engaged when in its retracted position, and a shoulder V^4 at one side of the notch V^2 governs the lug V^3 in closing the 75 gate.

Nail driving mechanism.—The nails when released by the gate T^3 are moved by gravity through the conduits T^4 which extend radially to a series of points preferably 80 equally spaced about the periphery of the package head. The nails in falling through the conduits will acquire considerable velocity, and to prevent recoiling when reaching the end of their course, a special construction is provided. This consists of a pocketed member W preferably mounted upon the revoluble member P' and having an inclined deflecting face W' . This pocket is registered with the corresponding conduit 85 T^4 at the time of release by movement of the gate T^3 , and the nail traveling down the conduit, head foremost, will strike against the inclined shoulder W' and will be deflected downward. The pocket W is so fashioned that the head of the nail is permitted to pass downward through a slot W^2 at the outer end of the pocket, while the body of the nail passes through a slot of restricted 90 width W^3 . This forms a shoulder W^4 for 100 engaging with the head of the nail and any recoil occasioned by the striking of the head against the outer end of the pocket will be prevented by the shoulder W^4 which prevents inward movement of the nail but permits it to drop downward through the slots W^2 and W^3 . Beneath the pocket W in its 105 position of rest, is a radial slot X in the member C , and alining with this slot is a nail driver X' which has an anti-friction roll X^2 engaging a cam slot X^3 in the under 110 face of the rotary member P' . The slot X^3 is of a form to hold the driver X' at the outward end of its movement during a part 115 of the revolution of the member P' and to 120 impart an inward radial movement to said driver during another portion of the rotary movement of the member P' . Every alternate driver engages a similar portion of the cam slot X^3 , while the intermediate drivers 125 engage a different portion of said slot, the arrangement being one to effect the simultaneous movement of one half of the drivers and alternately the simultaneous movement 130 of the other half. This will divide up the

work of driving the nails and decrease the power required for the machine. The rotary member P' is preferably completely housed in a cap member N^2 which is secured 5 to the annular member C and has dependent therefrom a flange N' on which the abutment N is formed. This flange N' also forms a journal for the rotary member P' which is provided with anti-friction rolls 10 N^4 engaging said flange.

The construction being as described in operation, a supply of nails is deposited in the hopper R , and after the assortment of a portion of these nails by the mechanism 15 described, the machine is in condition for operation. The workman first places the package body upon the table or plunger D centering it by engagement with the circular guide D' . At the same time the head 20 with the chine-hoop in engagement therewith is placed at the top of the body with the lower edge of the hoop just entered into engagement. Motion is then imparted to the machine by actuating the tripping pedal 25 L which throws in the clutch K and communicates motion from the shaft J through the gear train I to the crank E , and through the abutment F to the plunger D . The plunger is thus raised, carrying up the package 30 which is guided by the annular member M into engagement with the abutment N . Here further movement of the head and chine-hoop is prevented but the body continues to be forced upward until in full engagement with the head. This occurs before the crank has reached the upper limit of its movement and thus the plunger continues to rise but is permitted to do so without injury to the package by the compression 35 of the springs D^2 . Upon the completion of the engagement of the head with the cylindrical body the interrupted gear P^6 enters into mesh with the pinion P^2 , imparting rotary motion to the shaft P^4 and 40 thereby driving all of the mechanism at the upper end of the machine. This will instantaneously start the members P' in rotation causing the engagement of the rolls P with the stops Q^4 and in the further 45 movement of the member P' rocking the arms Q until arrested by the stops Q^5 . This presses said rolls inward against the return bent flange of the chine-hoop and during the further movement of the member P' said 50 flange will be rolled down against the cylindrical body.

During the operation just described the rotation of the annular member P' will actuate the nail drivers X' , one half of the number being first moved and at the completion 55 of their movement the other half are operated. The nails for this operation have previously been deposited in the radial slots X and are in the path of movement of the drivers which force them inward, the point 60

first penetrating the body and then the chine-hoop and the head. The V shaped portion of the chine-hoop forms a guide for directing the point of the nail to the apex, thus insuring that it will be properly directed in entering the wood of the head. In the mean while the other movable parts of the nailing mechanism are in operation, the member T being rotated to carry a series 70 of nails previously deposited in the pocket T' into reverse position and above the gate T^3 . The pockets W are also being carried by the movement of the member P' and are out of registration with the nail conduits T^4 and just at the completion of the movement of said member P' , the nails reversed by the member T will be above the gate T^3 , and the cam V will register its notch V^2 with the lug V^3 permitting the spring V' to snap open the gate T^3 . Thus just as the 80 pockets W are brought into registration with the conduits T^4 a set of nails is released by the gate T^3 and fall through said conduits into the pockets W , from which they drop into the radial slots X also in registration therewith. The nails thus deposited are in position for the succeeding operation. The nail assorting mechanism is also in operation during the movement just described, the shafts U' imparting motion through the 85 medium of the gear wheels U^2 to the gear cranks R^9 , and the latter reciprocating the pitmans R^8 , cross bars R^7 and fingers R^3 . The nails in contact with these fingers will be frictionally moved and will arrange 90 themselves in parallelism within the V shaped recesses R' , and during the successive reciprocations the lowermost nails in these recesses will drop into the slots R^2 . The heads however, are too large to pass 95 into the slots R^2 and will be supported upon the oblique flanges of the fingers R^3 . Thus the frictional engagement between the heads and the fingers R^3 will feed the nail in the slot R^2 downward through the slot beneath 100 the lug R^5 out from the hopper. As soon as the nail thus fed comes into full registration with the slot in the guide R^6 the body will drop through the slot and the nail assume a vertical position suspended by 105 the head.

The capacity of the assorting mechanism for the nails is in excess of the demand of the machine and as a consequence the nails will accumulate in the guide R^6 until the 110 slots thereof are filled. When they reach a point where the nail being drawn outward by the fingers R^3 is stopped by a nail in the slotted guide R^6 before the full length of the nail is in registration with the slot the nail 115 will be prevented from dropping through the slot, and consequently upon the return movement of the fingers R^3 it will be moved back again. Thus the feeding of nails is stopped until removal of nails from the 120

lower end of the series will afford sufficient space at the upper end for the deposit of more nails. In the heading of packages there may occur variations in size and particularly in the length of the body. This will not however, in any way interfere with the operation of the heading mechanism as the springs D^3 for supporting the yieldable seat D^2 will compensate for any variation in length.

10 What I claim as my invention is:

1. In a package heading machine, the combination with a movable support for the body of the package having a head in initial engagement therewith, of an abutment for

15 said head, means for moving said support to force the head into the body, said abutment and movable support together constituting a press, an annular member in fixed relation to said abutment surrounding the headed end of the package, radial guides in said annular member for nails, and means operating in sequence to the operation of said press for forcing nails inward in said

20 guides through said body and into the head.

2. In a package heading machine, the combination with an abutment for the head, of means for forcing the body of the package having a head initially engaged therewith

25 against said abutment, an annular member surrounding the headed end of said package in fixed relation to said abutment and having radial guides for nails, means for periodically depositing nails in said guides, and

30 means operating subsequently to the deposit of said nails and the engagement of the head with the body for driving said nails through the body into the head.

3. In a package heading machine, the combination with an abutment for the package head, of means for moving the head and body of the package against said abutment to complete the engagement thereof, an annular member surrounding said abutment in

45 fixed relation thereto having radial guides for nails, means for distributing a plurality of nails into the respective radial guides, and means for subsequently driving the nails from said guides through the body

50 into the head of a package.

4. The combination with a nail guide, of a conduit through which the nail is fed to said guide in a direction reverse to that in which the nail is driven, an abutment for 55 arresting movement of the nail in said conduit when in registration with said guide, means for preventing the recoil of the nail from said abutment, and drivers for the nails.

60 5. The combination with a series of radially arranged nail guides, of a holder for nails located centrally of said guides, means for periodically delivering nails from said holder corresponding in number to said

guides, conduits through which said nails are respectively conducted radially outward to said guides, stops for the nails when in registration with said guides, means for preventing the recoil of said nails, and drivers for said nails.

6. The combination with a series of radially arranged nail guides, of a holder for nails located centrally of said guides, means for simultaneously extracting from said holder a plurality of nails corresponding in number to said guides and for delivering the same head downward, conduits through which said nails are distributed to the respective guides, and drivers for the nails in their guides.

7. The combination of an annular member having a series of radially arranged guide channels in the upper face thereof, a rotary member above said annular member having a series of nail receiving pockets 80 movable into registration with said guide channels, nail delivery conduits communicating with said pockets when in registration with said guide channels, means for delivering a series of nails to said conduits 85 timed with the registration of said pockets, and drivers for the nails.

8. The combination of an annular member having a series of radially arranged guide channels in the upper face thereof, a 95 rotatable member above said annular member forming a cap for said channels and provided with a series of nail receiving pockets adapted for registration with said channels, nail delivery conduits discharging 100 into the respective pockets when in registration with said guide channels, said conduits having their receiving ends in alignment, means for delivering nails into the receiving ends of said conduits timed to 105 occur when said pockets are in registration with said conduits and channels, and drivers for the nails.

9. The combination of an annular member having a series of radially arranged nail 110 guide channels therein, drivers in alignment with said channels, a rotary member above said annular member having an operative engagement with said drivers, nail receiving pockets carried by said rotary member and 115 adapted for registration with said channels, nail delivery conduits discharging into said pockets when in registration with said channels and having aligned receiving ends, means for delivering nails into the receiving ends 120 of said conduits, and a gate controlling the delivery of said nails into said conduits timed to open when said pockets are in registration with said channels and conduits.

10. The combination with a series of radially arranged nail guides, conduits for receiving nails and delivering the same to the guides, and means for delivering to said conduits a plurality of nails headforemost, a gate for simultaneously opening said con- 125

6
duits to receive the nails from said delivering means, and drivers positioned in operative relation to said guides.

11. The combination with an annular member, having radially arranged nail guide channels therein, of drivers in alinement with said channels, a rotary member above said annular member having a cam for engaging and operating said drivers and 10 pocketed to register with said channels, nail delivery conduits discharging radially outward into said pockets when the latter are in registration with said channels, means for delivering nails headforemost to said 15 conduits, and a gate controlling the discharge of nails into said conduits timed to the registration of said pockets with the channels and conduits.

12. The combination with an annular 20 member, having a series of radially arranged nail guide channels, of drivers alined with said channels, a rotary member above said annular member forming a cap for said channels and provided with pockets for registration therewith, a cam upon said rotary member forming an operative means for 25 said drivers, conduits leading to said radially arranged nail guides and adapted to discharge into said pockets when in registration with said channels, means for delivering to said conduits nails headforemost, and means for turning the delivery of nails 30 into the conduits upon the registration therewith of the channels.

35 13. In a package heading machine, the combination with a support for the body of the package, of an abutment for the package head, means for effecting a relative movement between the support and the 40 abutment to force the head into the body, a member surrounding the abutment and in fixed relation thereto, a plurality of radial nail guides in said member, and means for driving the nails inward in said guides 45 and into the package.

14. The combination with a member having a plurality of guide channels in the upper face thereof, a rotary member above the first-mentioned member having a series of 50 nail-receiving pockets movable into registration with the guides, nail delivery conduits arranged to communicate with the pockets, means for delivering a series of

nails to the pockets, and drivers for the 55 nails.

15. The combination with a member having a plurality of guide channels, a second member having a series of nail-receiving pockets, said members being relatively rotatable to bring the pockets and channels 60 into registration, nail delivery conduits arranged to communicate with the pockets, means for delivering a series of nails to the pockets, and drivers for the nails.

16. The combination with a member having a plurality of guide channels, a second member having a series of nail-receiving pockets, said members being relatively rotatable to bring the pockets and channels 65 into registration, nail delivery conduits arranged to communicate with the pockets when the latter are in registration with the guide channels, means for delivering a series 70 of nails to the pockets, drivers for the nails, and means for operating the parts in timed 75 relation.

17. The combination with a revoluble member, of nail guides arranged in said member, drivers in alinement with said 80 guides, means for delivering nails to the respective guides, and a cam slot in said revoluble member engaged by said drivers.

18. The combination with a revoluble member, of a plurality of nail guides arranged in said member, drivers in alinement with the respective guides, means for delivering nails to said guides, and means for effecting a simultaneous movement of a portion of said drivers and for alternately effecting a simultaneous movement of the 90 remaining drivers.

19. The combination with a series of radially arranged nail guides, of feeding conduits communicating with said guides, means for feeding a plurality of nails headforemost to said feeding conduits, means for feeding said nails headforemost to said guides, and drivers for the nails arranged 95 in operative relation to the guides.

In testimony whereof I affix my signature 100 in presence of two witnesses.

HENRY C. HERR.
